TRIMMING MECHANISM FOR GRINDING
WHEELS

Richard John Bullows, Shirley, near Birmingham, England, assignor to The Gear Grinding Company Limited, Shirley, near Birmingham, England

Application December 26, 1941, Serial No. 424,557
In Great Britain February 22, 1941

4 Claims. (Cl. 125—11)

This invention has for its object to provide improved means for trimming the working surfaces of formed grinding wheels used in the grinding to predetermined shapes of the faces of gear wheel teeth, splined shafts, screw threads and the like.

In the accompanying sheets of explanatory drawings:

Figure 1 is a sectional side elevation of trimming mechanism constructed in accordance with the invention.

Figure 2 is a section on the line 2—2 of Figure 1.

Figures 3, 4 and 5 are respectively opposite end elevations and a plan of the mechanism shown in Figure 1.

Figure 6 is a view illustrating the cross sectional form of the part of a grinding wheel to be trimmed by the mechanism shown in Figures 1 to 5.

The mechanism shown in Figures 1 to 5 is adapted for trimming the working surfaces of a grinding wheel *a* used for grinding the teeth of gear wheels. As shown in Figure 6 the grinding wheel *a* has a pair of curved side surfaces *b*, a peripheral surface *c*, and rounded edges *d* between the side and peripheral surfaces, the surfaces *b*, *c* and *d* being shaped to correspond respectively with the adjacent faces of a pair of gear teeth, the base of the space between these faces, and a pair of rounded fillets situated at the junctions of the tooth faces and the base.

In carrying the invention into effect as shown, I employ a lever-like shaft consisting of long and short parts *f*, *e*, which at their adjacent ends are formed integrally with each other or secured together, the shaft being oscillatable about its own axis in the manner herein-after described. The short part *e* of the shaft is adapted to carry a pointed diamond or other suitable trimming tool *g*, and is so cranked or otherwise shaped that the tool can be arranged to extend radially inwards with its operative end situated at a distance from the axis of oscillation of the shaft corresponding to the radii of the two rounded edges *d* of the grinding wheel *a*. The shaft *e*, *f*, is rotatably mounted in any convenient bearing *h* which surrounds a portion of the long part *f* of the shaft, and which is provided at the end adjacent to the short part *e* of the shaft with a fork-shaped extension *i*, the latter being connected by a pair of coaxial and horizontal pivots *j* to a fork-shaped support *k* which is carried by a vertical pivot *m*. The pivots *j*, *m*, enable the bearing *h* and shaft *e*, *f*

to be rocked in each of two planes at right angles to each other in a hollow body part *n* through which the shaft extends, the vertical pivot *m* being mounted on a bracket *o* secured to one side 5 of the body part. If desired the bearing *h* may have associated with it any convenient resiliently mounted supporting member as *p* or a supporting spring. The end of the long part *f* of the shaft remote from the tool *g* lies between and can 10 co-operate with each in turn of the edges of a pair of fixed templates *q* adjustably mounted on the adjacent end of the body part *n*, the edges of these templates being shaped to correspond with the form to be imparted to the two curved side 15 faces *b* of the grinding wheel *a*. This end of the shaft is preferably provided with a roller *r* through which it can make contact with the templates *q*.

At any convenient position on the long part *f* 20 of the shaft between the bearing *h* and the roller *r* is formed or secured a short crank *s*, herein termed the driven crank, and above it within the body part *n* of the mechanism is mounted a rather larger crank *t* herein termed the driving crank, the latter being adapted to be actuated by any convenient means. In the example shown 25 the driving crank *t* is secured on a stub shaft *u* journaled in one side of the body part *n*, and is adapted to be actuated through a worm *v* and form wheel *v'* by a hand wheel *w*. The relative disposition of the two cranks *s*, *t*, is such that in the central position of the mechanism their 30 centre lines are in the same plane as shown. The two cranks *s*, *t*, are interconnected by a connecting rod *x*, the latter having universal pivotal connections *x'*, *x''* with the cranks. The end of the connecting rod *x* adjacent to the driving crank *t* is formed with an extension *y*, and in association with this extension is a controlling 35 spring *z* which in the example shown has the form of a helical compression spring. This spring *z* is mounted on a bar *3* secured in the body part *n*, and parallel with this bar is secured in the body part another bar *4* on which are 40 mounted a pair of slides *5* having apertured lateral projections *6* through which the bar *3* passes, the said projections being adapted to abut at their adjacent sides against opposite ends of the compression spring, and at their other sides against adjustable stops *7* on the body part *n*. 45 Also each of the slide projections *6* is connected by a slotted link *8* to the outer end of the extension *y* of the connecting rod *x*. When the connecting rod *x* is moved in one direction from its central position it actuates one of the slides 50

5 through one of the links 8 against the resistance of the spring 2, and when moved in the opposite direction it causes movement of the other slide through the other link also against the resistance of the said spring.

On the long part f of the shaft e, f, between the driven crank s and the roller r which cooperates with the templates q I mount a control member 9 which does not itself rotate but allows rotation of the shaft. The control member 9 is provided with a pair of adjustable stops 10 situated at opposite sides of the axis of the shaft e, f, and the driven crank s is provided at its opposite sides with abutments 11 which can engage the stops. The control member 9 is carried by any convenient means which will permit the required rocking of the shaft e, f, in each of two planes at right angles to each other. Thus, in the example shown the control member 9 is embraced by and pivotally attached to the open end of a fork 12 whose other end has a universal pivotal connection 13 with one end of a frame-like arm 14, the other end of the latter being pivoted to a stationary member 15, within the body part n, on an axis at right angles to that of the shaft e, f. The arm 14 is therefore capable of swinging only about a pivot axis at right angles to the axis of the shaft, but the fork 12 can swing in any direction. Moreover the fork 12 is connected by a helical tension spring z to the outer end of the extension y of the connecting rod x. Further there is provided on the body part n an adjustable stop 16 against which the end of the arm 14 connected to the fork 12 can abut under the action of the spring z.

To elucidate the mode of operation of the above described mechanism it is convenient to start with the cranks s, t, and connecting rod x in their central positions as shown, and the point of the tool g in contact with the centre of the periphery c of the grinding wheel a, the axis of the shaft e, f, then lying in the central plane of the grinding wheel, and the arm 14 being in contact with the stop 16. The first effect of movement of the driving crank t in either direction is to rock the connecting rod x about its pivotal connection with the driving crank. This rocking movement of the connecting rod x, which takes place as a result of the resistance of the spring 2 to movement of the connecting rod extension y, has the effect of swinging the shaft e, f, in a horizontal plane about the pivot m and so causing the point of the tool g to move across one-half of the wheel periphery c until arrested by contact of the roller r with the edge of one of the templates q. Continued movement of the driving crank t causes the driven crank s to rotate the shaft e, f, about its axis and so cause the tool g to trim one of the rounded edges d of the grinding wheel a to the required radius. This movement of the driven crank s is arrested when one of the crank abutments 11 makes contact with one of the stops 10 on the control member 9. Thereafter further movement of the driving crank t causes the shaft e, f, to swing in a manner determined by the interaction of the roller r with the edge of the adjacent template q, so causing the tool g to traverse the corresponding side face b of the grinding wheel a. During this movement the roller r is kept in contact with the said template q by the joint forces transmitted by the connecting rod x and the spring z which connects the latter to the control member 9. When the tool g reaches the end of its path further motion is prevented by the engagement

of a convenient part of the mechanism, such as one side of the driving crank t with a stop 17. At this stage the motion of the driving crank t is reversed, and the tool g is caused to re-trace its path until it reaches its initial position. Continued movement of the crank t beyond this position causes the shaft roller r to swing into contact with the other template q and to repeat the above described sequence of actions on the other 10 half of the wheel a.

It will be obvious that the mode of operating the mechanism above described may be varied, and the one just described has been selected for reasons of ease of description. It would be convenient in practice to start the trimming operation at one end of the path of the tool g where the latter would commence its action at one side of the wheel a, traverse one of the curved faces b, then pass around one of the rounded edges d 20 and across the periphery c, and after rounding the other rounded edge sweep over the other curved side surface.

By means for a mechanism as above described I am able to effect the trimming of the side faces and periphery of a grinding wheel by means of 25 a single tool and thereby ensure perfect continuity of the treatment of different portions of the working surfaces of the wheel, a condition which is difficult to obtain when two or more separate tools acting on different parts of the wheel are used. When as has been more usual in the past a plurality of tools are used, each tool is apt to wear unequally at different sides of its point, with a result that the wheel faces acted 30 on by the tools are not perfect reproductions of the shapes corresponding to the templates. By my invention this condition is also obviated or minimised, and the wear is more symmetrically distributed over the active portions of the tool.

40 The invention is not limited to the example above described as subordinate details of construction or arrangement may be varied to suit different requirements. If desired I may arrange for the mechanism to be actuated automatically instead of by hand. Also the body part 45 may be mounted on any conveniently arranged slide or slides enabling the tool to be brought into appropriate relationship with the wheel to be trimmed. Moreover a single appropriately shaped template may be used instead of a pair of templates as above described. Further the invention is not limited to the particular use above described as it is equally applicable with appropriate modification of detail to the trimming of 50 wheels required for grinding spline shafts, screw threads, and the like.

Having thus described my invention what I claim as new and desire to secure by Letters Patent is:

60 1. A grinding wheel trimming mechanism comprising the combination of a shaft adapted at one end to carry a trimming tool and at the other end to co-operate with at least one template, means for supporting the shaft whereby it can 65 be oscillated about its own axis and also in each of two planes at right angles to each other, a driving crank, a driven crank on the shaft, a connecting rod interconnecting the two cranks, a non-rotatable member mounted on the shaft 70 at a position between the driven crank and the end of the shaft adapted to co-operate with the template, interengageable parts on the said member and driven crank for limiting the angular movement of the latter crank, a spring interconnecting the said member and an extension of 75

the end of the connecting rod adjacent to the driving crank, and a second spring adapted to oppose movement of the said extension.

2. A grinding wheel trimming mechanism as claimed in claim 1 and having in combination a fork-embracing and pivotally connected to the non-rotatable member on the shaft, and an arm pivotally supported at one end on an axis at right angles to the axis of the shaft, the other end of the arm having a universal pivotal connection with the fork.

3. A grinding wheel trimming mechanism as claimed in claim 1 and having in combination a hollow body part through which the shaft extends, a bar secured in the body part and having the second spring mounted on it, this spring having the form of a helical compression spring, another and parallel bar secured in the body part, a pair of slides mounted on the latter bar and adapted to abut against opposite ends of the said second spring, and slotted links connecting the slides to the outer end of the extension of the connecting rod so that either slide can be actuated by the connecting rod against the resistance of the said second spring.

4. A grinding wheel trimming mechanism comprising the combination of a shaft adapted to carry at one end a trimming tool and at the other end to co-operate with at least one template, 5 means for supporting the shaft whereby it can be oscillated about its own axis and also in each of two planes at right angles to each other, a driving crank, a driven crank on the shaft, a connecting rod interconnecting the two cranks, 10 and controlling means whereby the tool under the action of the driving crank is caused to traverse a desired path determined in part by the template, the means for supporting the shaft having in combination a bearing surrounding the 15 shaft at a position near the end adapted to carry the trimming tool, and a supporting member which is movable about a vertical axis and to which the bearing is pivoted on a horizontal axis, the shaft being shaped so that the tool can be 20 arranged to extend radially inwards with its operative end spaced from the axis of the shaft.

RICHARD JOHN BULLOWS.
